BARN, ETC.

Joseph Burgad, Strasburg, N. Dak.

Application December 10, 1928, Serial No. 324,941

5 Claims. (Cl. 20—1)

This invention primarily relates to a means for sealing openings in a barn, warehouse, or like building against unauthorized intrusion therethrough more effectively than previously has been the case.

In respect of the door openings, the instant invention contemplates two separately operable closures—to wit, an inner door and an outer door—for each outside door opening, relatively so arranged that the outside door can be opened and closed when the corresponding inner door is open and cannot be opened when said inner door is closed, together with suitable fastening or locking means and suitable opening means and an opening and closing means for each inner door. As to one of said door openings the invention contemplates that it shall be provided for ingress and egress into and from an otherwise sealed building and that its inner door will be opened and closed only from a place entirely outside of the building itself and which place is protected against unauthorized intrusion; and as to any other outside door opening with which the building is provided the invention contemplates that the inner door thereof shall be opened and closed, and also tightly secured when necessary as additional protection, only from the inside of the building and whose securing means are inaccessible from the outside of the building.

Considering the building in its entirety, it is contemplated to provide sealing means for the several window openings and door openings, whereof the means for sealing the window openings are operated from within the building, the means for sealing one outside door opening is of dual nature, that is includes an outside door and an inside door, so arranged with relation to each other that the outside door can be opened and closed only when the inside door is open and said inside door is provided with means which prevents its being opened from the outside of the building, and the means for sealing another outside door opening, likewise is of dual nature since it includes an outside door and an inside door, but the latter door is operable only from a protected place outside the building. It will be understood that the latter doorway affords egress for the operative after he has closed and sealed all of the window and outside door openings from within the building.

The invention also contemplates the provision of locking means of special nature for the inner door which forms a member of the sealing means for one door opening and for the sealing means for the window openings, accessible only from the inside of the building.

The dual doors, arranged one inward of the other, may be mounted for either sliding or swinging movement as found to be most convenient and the particular means for opening and closing

an inner door or doors will, of course, be selected in accordance with the character of doors to be operated thereby.

One of the special features of this invention is the utilization of a pair of doors, arranged one inward of the other, and to swing in opposite directions relatively to each other and to the opening sealed thereby, both in an inward direction. Doors of this character are herein illustrated for sealing what may be regarded as being the main opening to the building and need not essentially be provided with means for operating the inner door. A further special feature, contemplated by the invention in relation to the inner door last mentioned, is that its lateral edges project beyond the lateral edges of the corresponding outer door and lie against the door frame and with the inner surface of the part between its said edges in flatwise engagement substantially throughout its entire area with the entire inner surface of the outer door. As thus arranged the laterally projecting edge at the side of the inner door opposite the hinge affords provision for an appropriate fastening means, such as that herein illustrated and hereinafter described, and which fastening means will not be noticed from the outside of the building and cannot be reached from the latter place. A door of this character need not be provided with means for opening it and closing it unless it is too heavy to be opened and closed by hand, in which event any suitable opening and closing means may be employed.

A further special feature contemplated by the invention is that the door which is to be used for ingress and egress of the attendant and which is to be operated from a remote point outside of the building, is of sliding nature and that the means for operating it shall be entirely concealed from view, in addition to being controlled by a means which is outside of the building and protected against intrusion.

It will be apparent that the sealing means hereinbefore referred to is particularly useful upon barns, warehouses and like buildings which are unattended during the night or at other times, and affords such full protection as to render the building safe against unauthorized intrusion, thereby eliminating the necessity of an attendant or watchman.

While I have illustrated and will hereinafter describe, in detail, a particular embodiment of the invention, and while I would have it understood that I do not restrict myself to all of the details of said particular embodiment, I wish at the same time to have it understood that my invention essentially calls for the utilization of two doors, one inward of the other, for every door opening which is to be sealed and in respect of the opening provided for the ingress into

the building and for the final egress of the person who locks up the building that the inner door which forms a member of the sealing means for said opening can be opened and closed only from 5 the outside of the building and by means which are protected against operation by an intruder. As hereinbefore stated a material feature in respect of the sealing means for each outside door opening is that the inner and outer doors which 10 conjointly seal the same are so correlated that the inner door when in its closed position prevents the opening of the outer door.

Referring to the accompanying drawings:

Fig. 1 is a diagrammatic sectional view illustrating a means for operating a closure in one building from a position in another building;

Fig. 2 is a side elevation of a building equipped with closure operating and locking devices embodying my invention;

20 Fig. 3 is a front view of said building;

Fig. 4 is a fragmentary sectional view taken longitudinally through the front portion of the building, on line 4—4 of Fig. 8;

Fig. 5 is a fragmentary section taken transversely through the building;

Fig. 6 is a section, taken on line 6—6 of Fig. 8;

Fig. 7 is a vertical section taken on line 7—7 of Fig. 8;

Fig. 8 is a horizontal sectional view through 30 the entire building taken on line 8—8 of Fig. 2;

Fig. 9 is a perspective view of a locking screw used for fastening the various closures;

Fig. 10 is a perspective view of a tool adapted to operate the screw shown in Fig. 9; and

35 Fig. 11 is a sectional detail view taken on line 11—11 of Fig. 1.

As indicated in Fig. 8, the building (here shown as a barn or the like) is provided at the front with a central doorway A and with windows B and C at opposite sides of the door. At one side of the building there is a door E and three windows F, G and H; and at the other side there are two windows J and K, and a door L. It is of course to be understood that this particular arrangement of doors and windows is merely illustrative and is not at all essential insofar as the invention is concerned.

Referring first to the doorway A, with particular reference to Figs. 5 and 8, it will be observed 50 that this is sealed by an inner door 10 and an outer door 11. Both of these doors open inwardly, door 10 pivoting about hinges 12 at one side, and door 11 pivoting about hinges 13 at the other side. When these doors are closed, they lie flat against each other, as shown in Figs. 5 and 8, and they may be locked in this position by passing a pin through a suitable staple 14 which is adapted 55 to pass through a slot near the edge of door 10 when the latter is closed. Obviously, when the doors have been thus locked in closed position they cannot be opened from the outside of the building. It should be particularly noticed that whereas the outer door cannot be opened when the inner door is closed, yet said inner door may be opened or closed without affecting the position of the outer door, there being no connections between the doors. Both of these doors 10 and 11 may be formed of any suitable material, but are 60 preferably formed of sheet metal where a high degree of protection is required.

70 Window B is adapted to be covered by means of a sliding shutter 15, preferably formed of sheet metal and mounted to slide vertically in a metal frame 16 which is securely fastened to the outside 75 of the building and has a U-shape in cross sec-

tion to provide guideways receiving the edges of the shutter. In Figs. 3 and 4 the shutter is shown in its raised position, wherein it securely guards ingress through the window opening. The shutter is adapted to be locked in this position by means of a screw 17 of the form shown in Fig. 9. This screw is operable only from the inside of the building, being provided with a head 18 located at the inside and with a threaded extremity engaging a threaded aperture in the lower edge of shutter 15. The screw is adapted to be conveniently operated by means of the tool shown by Fig. 10. This tool is formed with a pair of projections, or teeth, 19 which are adapted to engage a pair of sockets 20 in the head 18 of the screw. Shutter 15 is operable from the inside of the building by means of a flexible member 21, such as a chain, cord, or rope. This member has one end secured to the upper edge of shutter 15, passes thence over a guide pulley 22 mounted in a small opening in the wall of the building, and passes downwardly therefrom on the inside of the building and is wrapped around the windlass of a drum 23 which is mounted in suitable brackets secured to the inner wall of the building. After the window has been closed and the shutter raised to cover the window opening it is obvious that no one outside of the building can raise the window.

An alternative means is illustrated for mounting and operating the shutter of window C at 105 the opposite side of the door in order to indicate the variations that can readily be made in carrying the invention into practice. This window has a shutter 24 which is hinged at its upper edge at 25 and is adapted to be operated from the inside of the building by means of a rope or chain 26 secured to the shutter at the lower edge thereof. This rope passes over a pulley 27 mounted in a small opening in the building wall and thence passes downwardly on the inside of the building 115 and around the barrel of a windlass similar to windlass 23. The shutter is adapted to be locked in closed position by means of a screw 17, in the same manner as shutter 15.

Window K has a shutter 30 which may be 120 mounted and operated in the same manner as shutter 15 of window B. The shutter is slidably mounted for vertical movements in a frame 31 and is operable by a rope 32 which passes over a pulley 33 mounted in an opening in the side 125 wall of the building and passes downwardly therefrom inside the building and around the barrel of a windlass 34.

The shutter of window J may be mounted and operated in a somewhat different manner than 130 either of the shutters described above. This window is provided with a shutter 35 which is mounted for horizontal sliding movements in a guideway 36 securely fixed to the outside of the building. This shutter is operable from the inside of the 135 building by a flexible member, or rope 37 secured to an eyebolt 38. One portion of rope 37 extends from the eyebolt 38 to and over a guide pulley 39 and thence over one sheave of a pulley 40 and the other portion extends from the eyebolt directly 140 over the other sheave of pulley 40. The two portions of the rope extend from pulley 40 through an opening in the building and thence around the barrel of a windlass 41, the two portions being wound around said barrel in opposite directions, 145 so that when the windlass is rotated one rope will be paid out while the other is drawn in, thus positively moving the shutter 35 in either direction according to the direction of rotation of the windlass. The shutter is adapted to be locked 150

in closed position from the inside of the building by a locking screw such as 17.

Windows F, G and H are provided with shutters 42, 43 and 44, respectively, the said shutters being rigidly connected together and being adapted to be simultaneously operated by mechanism which will now be described. Secured to an eyebolt 45 on shutter 42 is a rope 46 which passes around a pulley 47 mounted on the outside of the building 10 and thence through an opening in the building and around a pulley 48 mounted on the inside of the building and has its extremity secured in a hole formed in one end of a rack bar 49, which is slidably mounted for horizontal movements on 15 suitable ways inside the building. The other end of the rack bar has attached thereto one end of a rope 50 which passes around guide pulleys 51 and 52 mounted respectively inside and outside the building, the rope passing from pulley 52 and being secured to an eyebolt 53 on shutter 44. For 20 operating rack bar 49 there is provided a pinion 54 mounted for rotation above the rack bar and having rigid therewith a crank handle 55. The shutters are mounted for horizontal sliding movements in guideways 56, and, by the mechanism described, can be operated only from inside the building. These shutters are adapted to be locked from the inside as is the case with all 25 the shutters, by screws such as 17 illustrated in Fig. 8.

It will be noticed that each of the several shutters hereinbefore referred to is of solid, as contradistinguished from slatted, construction and that in every instance the operating means therefor includes a flexible member which extends 30 from the outside to the inside of the building together with an operating element which is inaccessible from the outside of the building, and it will be noticed also that each shutter is locked 35 by a screw which also is inaccessible from the outside of the building and further can be operated only within the building and by a device specially fitted thereto. This location of the operating member for opening a shutter and of the 40 member by which the shutters is locked in closed position, together with the particular nature of said locking member and the fact that even if reached it can only be operated by a device specially fitted thereto, co-operate in making it practically impossible for an unauthorized person to 45 find entrance into the barn or warehouse through any of the window openings.

The side doors E and I are provided with horizontally slideable inner doors 57 and 58, respectively, these doors being mounted inside of the building in suitable guides 59 and 60. The door 57 is adapted to be operated by a flexible connection, or rope, 61, which passes over guide pulleys 62, 63, and 64 and has its end portions wound 50 in opposite directions about the barrel of a suitable windlass (not shown), similar to windlass 41, whereby rotation of the windlass will slide the door positively in either direction.

The inner door 58 is adapted to be operated 60 from a point outside the building, as indicated in Fig. 1. Preferably this point is located in another building, which may be the residence to which the outbuilding is appurtenant. As indicated, the two buildings are connected by an 65 underground passage or conduit 65 through which passes the flexible rope or chain 61a for operating the inner door 58. The rope is secured to an eyebolt 66 on the door and thence passes in one direction to and about a guide pulley 67 and 70 thence passes back and over a guide pulley 68.

The rope passes in the other direction from the eyebolt to and over a guide pulley 69, and the two runs of the rope thence pass downwardly and over guide pulleys 70 and thence horizontally through the conduit and around guide pulleys 71 and thence upwardly and over a windlass 72 provided with a suitable operating handle. The inner doors 57 and 58 are preferably mounted on rollers 73 rotatable in the lower guideways of the doors. 85

It will be clear from the foregoing that all the closures of the building to be protected are provided with shutters or inner doors, all of which but one are operable from the inside of the building, and that this one closure or door is operable from a point which is not accessible to one seeking improper access to the building. The result is that the closures can be securely protected by devices operable only from the inside of the building or from a protected point, such as the dwelling house to which the building is appurtenant, and consequently the building can be closed in a very effective manner against all unauthorized entry. 90 95

Now having fully described my invention, what I claim as new and desire to secure by Letters Patent of the United States is:

1. In a building having a door opening inner and outer doors hinged respectively at opposite sides of the door opening and adapted to lie flat against each other when in closed position, the said inner door thereby operating to prevent opening of the outer door, and means operable only from the inside of the building to secure the inner door in closed position. 100 105 110

2. In a building having a door opening inner and outer doors hinged respectively at opposite sides of the door opening and adapted to lie flat against each other when in closed position, said inner door thereby operating to prevent opening of the outer door and having a slot near its free edge, a fixed staple adapted to project through said slot when the door is closed, and a pin adapted to engage the staple to hold the door closed. 115

3. In a building having a door opening; inwardly opening inner and outer solid doors hinged respectively at opposite sides of the door-opening and each when closed completely closing the opening, said doors correlated to lie flatwise against each other throughout their entire confronting surfaces when closed, the inner door having both of its longitudinal sides projecting over the corresponding edges of the door opening and having its hinges within the building and inaccessible from the outside, and means at the other side 120 125 130 of the opening and inaccessible from the outside of the building for securing the inner door in its closed position.

4. A barn, warehouse or like building, comprising an opening for ingress and egress and an outer door and an inner door co-acting to seal said opening, said outer door being arranged forward of and in juxtaposition to the inner door and being mounted to open inward toward the latter, and said inner door being mounted to have movement to opened and closed positions independently of the outer door and being arranged relatively to the latter to prevent, when closed, access to the outer door from the inside of the building and movement of said outer door to opened position, 135 and means for opening and closing said inner door, operable from a place outside of and remote from the building. 140 145

5. A barn, warehouse or like building having a door opening and provided with means for seal- 150

ing said opening against unauthorized ingress or egress into or from the building through the same: said means including an outer door, a solid inner door disconnected from the outer door and mounted to have sliding movement independently of movement of said outer door and into and out of registration with the same, and serving when closed to prevent opening movement of the lat-

ter door, and operating connections for opening and closing said inner door, said connections extending from said inner door to a remote point outside of the building and having an operating member inaccessible from any point within the building. 80
